UNITED STATES PATENT OFFICE.

THOMAS LUND, OF BEVERLY, MASSACHUSETTS, ASSIGNOR, BY MESNE ASSIGNMENTS,
TO UNITED-XPEDITE FINISHING COMPANY, OF BERWICK, MAINE, A CORPORATION
OF MAINE.

BURNISHING-MACHINE.

1,303,931.

Specification of Letters Patent. Patented May 20, 1919.

Application filed November 28, 1916. Serial No. 133,867.

To all whom it may concern:

Be it known that I, THOMAS LUND, a citizen of the United States, residing at Beverly, in the county of Essex and State of 5 Massachusetts, have invented certain Improvements in Burnishing-Machines, of which the following description, in connection with the accompanying drawings, is a specification, like reference characters on the 10 drawings indicating like parts in the several figures.

This invention relates to a burnishing machine which is provided with a rotary tool adapted to be heated and by means of which 15 wax may be applied to the surface to be burnished.

In burnishing the heels of boots and shoes, it is common to employ a rotary tool which is heated and whose periphery is supplied 20 with wax or other finishing medium which will be transferred to the surface to be burnished. Such tools are frequently heated by the external application of a gas flame but such an arrangement is disadvantageous on 25 account of the danger of setting fire or of burning the operative's hands. Wax is usually applied to the periphery of the tool by means of a rotary disk one side of which dips in a well of wax and another portion 30 of which runs in close proximity to the tool periphery. Inasmuch as the supply of wax is independent of the use of the machine, it will be seen that the wax may accumulate upon the tool in the case of considerable intervals between the applications of work to 35 the tool.

The object of the invention is to provide an improved burnishing machine wherein the difficulties noted will be avoided. The 40 invention contemplates the provision of a rotary tool which shall be heated by steam supplied to the interior of the tool while the same is rotating. It also contemplates a tool in which wax is supplied directly to the periphery of the tool through the interior thereof while the same is rotating, the tool being preferably arranged so that the supply of wax is determined by the application of work to the tool.

50 A feature of the invention consists in an arrangement for preventing the formation of steam pockets which might cause condensation and imperfect operation of the steam heating device.

55 Another feature of the invention relates

to the arrangement of the means for supplying wax to the tool while it is being rotated and especially to the arrangement whereby the wax supply pot, together with all parts of the communicating passage between the 60 same and the wax chamber of the tool, are continuously and thoroughly heated.

As here shown, the rotary tool is preferably provided with a plurality of chambers, certain of which are adapted to be supplied 65 with steam and others of which are adapted to be supplied with melted wax while the tool is rotating, the latter chamber or chambers communicating with the work surface of the tool by means of openings which are 70 preferably provided with valves controlled by the application of work to the tool. The wax and steam chambers are preferably adjacent in order that the wax may be maintained in melted condition by the heat supplied from the steam chamber.

The scope of this invention is to be determined from the appended claims and it will be understood that it is not limited to the exact arrangement described in the specification and shown in the accompanying drawings in which;

Figure 1 is a side elevation of a burnishing machine constructed in accordance with my invention and including my novel burnishing tool;

Figs. 2 and 3 are longitudinal sections through the end bearings of the burnishing machine;

Fig. 4 is a section through the burnishing tool taken upon the line 4—4 of Fig. 5; and

Fig. 5 is a side elevation, partly in section, of the burnishing tool.

A frame 10, of any suitable construction, is herein shown as adapted to be secured to 95 a work bench and is provided with a plurality of bearings 12, 14 and 16 which support a hollow shaft 18 upon which is mounted the burnishing tool 20 and a driving pulley 22. This shaft may be rotated from any suitable source, as for example, by means of a belt 24. The tool 20 is securely held in fixed relation to the shaft by means of a collar 21 (Fig. 4) pinned to the shaft and having a projection 23 entering a notch in 105 a flange 25 on the tool and clamped thereto by means of a screw threaded collar 27. A bracket 26, here shown as formed integral with the frame, is designed to support a rotatable work rest 28 and an adjustable 110

tread rest 30. These rests form no part of the present invention and are of the type more fully illustrated in the patent to Pease No. 959,880 of May 31, 1910. The tread 5 rest 30 is mounted upon a slide 32 which is adjustable longitudinally of the shaft by means of a screw 34. Provision is also made for adjusting the tread rest toward and away from the tool by means of a screw 36 10 and for varying the inclination of the shoe supporting face of the tread rest to the plane of rotation of the burnishing tool by means of a screw 38, all of which parts are more fully described in the patent above 15 mentioned.

Referring to Figs. 4 and 5, it will be seen that the burnishing tool is provided with a plurality of chambers, of which alternate ones 40 are adapted for the admission of 20 steam to heat the tool and are provided with openings 42 and 44 communicating with suitable openings in the hollow shaft to provide for the admission and exhaust of steam to said chambers. It should be noted that 25 these openings are arranged adjacent to the lateral face of the burnishing tool in order that steam, admitted through the opening 42, shall traverse practically the whole of the chamber 40 before passing through the 30 exhaust opening 44 thereby avoiding pockets wherein condensation can take place and the proper heating of the tool prevented. Steam may be supplied to the right end of the hollow shaft 18 through a pipe 46 connected with an opening 48 (Fig. 3) in the bearing 16. Suitable packing 50, adapted to be compressed by an annular threaded ring 52, is provided within the bearing to make the joint between the same and the 40 hollow shaft steam tight without interfering with the free rotation of the shaft. An oil cup 54 allows for the lubrication of the shaft. The exhaust steam will pass by way of the left end of the hollow shaft 18. 45 through openings 56 therein (Fig. 2) which communicate with an annular duct 58 in the bearing 12 and thence with an exhaust pipe 60. The open end of the hollow shaft 18 is closed by means of a screw plug 62 and oil 50 cups 64 are provided for the lubrication of the bearing.

A partition 66 is arranged within the hollow shaft 18, in the plane of the burnishing tool, to separate the inlet and exhaust portions of said shaft and at the same time provide for the support of a pipe 68 mounted to rotate therewith within the hollow shaft and communicating by means of openings 70 with one or more wax chambers 72. 55 These chambers are provided with openings 74 communicating with the work surface of the tool and the flow of wax therethrough is controlled by means of suitable valves 76 here shown as comprising spring pressed 60 balls 78 which project slightly beyond the 65

work surface of the tool and are adapted, when depressed, to allow wax to be supplied to the work surface. As the tool is rotated in contact with the surface of the work these balls 78 will roll within the valve openings 70 thus bringing a wax coated portion to the surface of the tool and at the same time avoiding the production of tool marks such as would result from the use of a reciprocating valve. The right end of the pipe 68 is 75 supported in the bearing 16 concentrically with the hollow shaft 18, partly by a perforated spacer 69, and communicates with a wax pot 80 (Fig. 3) which is shown as provided with a hinged cover 82 whereby 80 wax may be supplied thereto. This wax pot is preferably provided with an annular jacket 84 whereby the live steam supplied through the pipe 46 will circulate around said jacket and melt the wax in the pot. 85

The work surface of the burnishing tool may be of any suitable form and it is herein shown as provided with depressions 86 and with suitable grooves or markings 88 whereby the wax will be evenly distributed 90 over the surface of the tool, and hence over the work to be burnished, and the production of tool marks upon the work avoided. It will be noted that the disposition of the 95 various depressions and markings on the face of the tool causes a rubbing action first outwardly toward the margins of the tool and then inwardly away from these margins and lengthwise of the edge. On account of the depressions 86 in the periphery of the 100 work-rubbing surface, the extent of the burnishing surface between the opposite edges of the tool alternately increases and diminishes as the tool advances over the work. By means of the staggered arrangement of the 105 wax outlets along the periphery of the surface of the tool, the supply of wax is more evenly distributed along the heel to be burnished.

The operation of the machine will be similar to that of finishing machines well known in the art and, if used in burnishing the heel of a shoe, for which the particular construction illustrated is especially adapted, the tread of the heel will be rested against the 110 tread rest 30 and the heel face maintained in contact with the work surface of the tool while being rested against and rotated upon the work rest 28. A rapid rotation of the heated tool in contact with the face of the 115 heel or other work will cause the same to be highly burnished. In addition, it is usually found desirable to apply wax to the surface of the tool and hence to the surface of the work and it is seen that by means of this invention, wax is supplied to the work surface of a tool while the same is rotating. Since the flow of wax is controlled by the application of work to the tool, wax will be supplied only while the machine is being 120 125 130

used and hence an accumulation of wax will be avoided during intervals between the application of the work. By keeping the wax pot and the pipe communicating between 5 said pot and said wax chambers of the tool heated, as well as by heating the tool itself, hardening of the wax during its passage through the machine is avoided. This action is especially assisted by the adjacent location of the steam and wax chambers. It 10 will be understood, however, that my invention is applicable to a tool which is not supplied with wax and that it is not essential that it be utilized for burnishing the heel of 15 a shoe since those skilled in the art will readily perceive how the same may be adapted for other purposes.

Having thus described my invention, what I claim as new and desire to secure by Letters Patent of the United States is:—

1. In a machine of the type described, a shaft, a rotary finishing tool mounted thereon provided with a finishing surface surrounding a chamber, and means for introducing steam into said chamber through the shaft of said tool near one side of the finishing surface, said chamber being provided with an opening near the opposite side of the finishing surface for exhaust of the steam.
2. In a machine of the type described, a plurality of bearings, a shaft in said bearings, a rotary finishing tool mounted on said shaft and provided with a chamber, one of said bearings having means for introducing steam to said chamber, and another of said bearings having means for exhausting steam from said chamber.
3. In a machine of the type described, a shaft, a rotary finishing tool mounted thereon, means rotating with said tool for supplying wax to the work surface, and means for supplying steam through said shaft to heat said tool and melt the wax.
4. In a machine of the type described, a rotary burnishing tool, means for heating said tool, a source of wax supply external to the tool, and means for supplying wax to the work surface from the source through the interior of the tool while the same is rotating.

5. In a machine of the class described, a movable finishing tool provided with a passage communicating with its work surface, a source of finishing medium fixed relatively to the tool, and means for supplying the finishing medium from the source to the passage during the movement of the tool.

6. In a machine of the type described, a rotary finishing tool provided with a chamber communicating with the work surface of the tool, and means for supplying wax to said chamber while the tool is rotating.

7. In a machine of the type described, a shaft, a rotary finishing tool mounted thereon and provided with a chamber communi-

cating with the work surface of the tool, and means for supplying wax through said shaft to said chamber.

8. In a machine of the type described, a rotary finishing tool provided with a chamber communicating with the work surface of the tool and adapted to be filled with wax, and means governed by the application of work to the tool for controlling the flow of wax.

9. In a machine of the type described, a shaft, a rotary burnishing tool mounted thereon, a wax reservoir, and a connecting passage leading from the work surface of said tool through said shaft to said wax reservoir whereby wax may be supplied to the work surface while the tool is rotating.

10. In a machine of the type described, a shaft, a rotary finishing tool mounted thereon and provided with a chamber communicating with the work surface of the tool, and a fixed wax receptacle, said shaft being provided with a passage connecting said receptacle and the chamber.

11. In a machine of the type described, a shaft, a rotary finishing tool mounted thereon and provided with a chamber communicating with the work surface of the tool, means for supplying wax through said shaft to said chamber, and means for internally heating said tool.

12. In a machine of the type described, a shaft, a rotary finishing tool mounted thereon provided with a chamber communicating with the work surface of said tool and adapted to be filled with wax to supply the work surface, and means for supplying steam through said shaft to heat said tool and melt the wax.

13. In a machine of the type described, a rotary finishing tool provided with a plurality of chambers, one of said chambers communicating with the work surface of the tool, means for supplying wax to the latter chamber while the tool is rotating, and means for supplying steam to another chamber while the tool is rotating to heat the tool and melt the wax.

14. In a machine of the type described, a hollow shaft, a plurality of bearings for said shaft, a rotary finishing tool mounted on the shaft and provided with a plurality of chambers, one of said chambers communicating with the work surface of the tool, means for supplying wax through one of said bearings to the latter chamber, means controlled by the application of work to the tool for controlling the flow of wax, and means for supplying steam through a bearing to another chamber for heating said tool.

15. In a machine of the type described, a shaft, a plurality of bearings for said shaft, a rotary finishing tool mounted on said shaft provided with a plurality of chambers, one of said chambers communicating with the

work surface of the tool, means controlled by the application of work for controlling the communication between said chamber and the work surface, means for supplying 5 wax through one of said bearings to said chamber, and means for supplying steam through one of said bearings to another chamber, said shaft being provided with an exhaust passage through a bearing remote 10 from the one through which the steam is introduced.

16. In a machine of the type described, a frame, bearings on said frame, a hollow shaft mounted in said bearings, a tool 15 mounted on said shaft and provided with chambers one of which communicates with the work surface of said tool, a wax pot mounted on the frame, connections between said wax pot and the chamber extending 20 through the shaft, a steam jacket around said wax pot communicating with a passage in said shaft and with a chamber in said tool, and means for supplying steam to said jacket and the passage in the shaft to melt 25 the wax.

17. In a machine of the type described, a hollow shaft, a rotary tool mounted thereon provided with a plurality of chambers, one of said chambers communicating with the 30 work surface of the tool, a pipe within the hollow shaft communicating with the latter chamber to permit the supplying of wax thereto, and means for supplying steam to another chamber of said tool through the 35 space in said hollow shaft surrounding said wax supply pipe.

18. A movable finishing tool provided with a wax chamber which communicates with the work surface of the tool, and a 40 valve controlling the communicating passage having a controlling member projecting beyond the surface of the tool and arranged to roll when the tool moves along the surface of the work whereby the production 45 of tool marks by the valve controlling member is avoided.

Copies of this patent may be obtained for five cents each, by addressing the "Commissioner of Patents, Washington, D. C."

19. A movable finishing tool provided with a wax chamber communicating with the work surface of the tool, the communicating passage being provided with a substantially spherical movable member adapted to roll when the tool moves in contact with the work so as to bring a portion of said member which is coated with wax in the chamber to the outside to apply wax to 55 the work.

20. In a machine of the type described, a rotary finishing tool provided with a wax chamber communicating with the work surface of the tool, and means for controlling 60 the flow of wax through said communicating passage comprising a spring pressed ball valve arranged so that the said ball projects slightly beyond the work surface of the tool whereby the same will be depressed 65 upon the application of work.

21. In a machine of the type described, a rotary finishing tool provided with a plurality of chambers, certain of said chambers being adapted to be filled with wax and 70 communicating with the work surface of the tool, others of said chambers being adapted to be heated by the introduction of steam, one of said steam chambers being adjacent to one of said wax chambers. 75

22. In a machine of the type described, a rotary finishing tool provided with a plurality of chambers communicating with the work surface of the tool and adapted to be filled with wax, and means interposed between said wax chambers for internally heating said tool. 80

23. A movable finishing tool provided with a wax supply passage connected with the work surface of the tool, and a member 85 contacting with the work and controlling the flow of wax from the passage, said member being movably mounted to prevent it from marking the work.

In testimony whereof I have signed my 90 name to this specification.

THOMAS LUND.
